UNITED STATES PATENT OFFICE.

WILLIAM C. MEYER, OF BEVERLY, MASSACHUSETTS, ASSIGNOR TO UNITED SHOE MACHINERY CORPORATION, OF PATERSON, NEW JERSEY, A CORPORATION OF NEW JERSEY.

SHOE-SEWING MACHINE.

Application filed August 8, 1919. Serial No. 316,241.

To all whom it may concern:

Be it known that I, WILLIAM C. MEYER, a citizen of the United States, residing at Beverly, in the county of Essex and State of Massachusetts, have invented certain new and useful Improvements in Shoe-Sewing Machines; and I do hereby declare the following to be a full, clear, and exact description of the invention, such as will enable others skilled in the art to which it app pertains to make and use the same.

This invention relates to shoe sewing machines of the class provided with a straight hook needle and with a rotatable work supporting horn arranged to extend within the shoe, such machines being generally known in the art as machines of the McKay type.

In certain machines of this type, the tension mechanism comprises a tension wheel mounted on a shaft rotatably mounted in the base of the horn, and devices for retarding the rotation of the tension wheel shaft to apply tension to the thread. With this construction oil, wax or dirt is often deposited upon the uppers of shoes while they are being sewn through contact of the uppers with the parts of the tension mechanism, and the stock is thereby discolored and soiled. This is a serious disadvantage, particularly when shoes of light or delicate coloring are being manufactured.

The primary object of the present invention is to produce a machine of the McKay type having a tension mechanism constructed and arranged in the above manner in which the shoe will be protected from contact with the parts of the tension mechanism.

With this object in view the invention consists in the provision of an enclosing casing for the tension device involving certain novel and improved constructions, arrangements and combinations of parts hereinafter described and particularly pointed out in the claims the advantages of which will be readily understood and appreciated by those skilled in the art.

The invention will be clearly understood from the accompanying drawings illustrating the invention in its preferred form, and the following detailed description of the constructions therein shown.

In the drawings Figure 1 is a view in front elevation of a portion of a McKay sewing machine embodying the invention; Fig. 2 is a view in front elevation illustrating the base of the horn and associated parts with certain of the parts in different positions from those in which they are shown in Fig. 1; Fig. 3 is a detail plan view illustrating the enclosing casing detached from the machine; and Fig. 4 is a detail view in side elevation illustrating the tension mechanism.

The machine illustrated in the drawings comprises a vertically reciprocating straight hook needle 2, a feed point or awl 4, a presser foot 6, and a rotatable work supporting horn 8, all of which parts have the same general construction, arrangement and mode of operation as is usual in machines of the McKay type. The horn is formed with the usual groove 10 through which the thread passes from the base of the horn to the whirl located in the tip of the horn, and is provided with a guard 12 inserted in the outer portion of said groove to enclose the thread. The horn guard is held in place within the groove 10 by means of a spring pressed latch pin 14 mounted to slide longitudinally in the wall of the horn, the inner end of which is arranged to engage in a recess in the horn guard. A knob 16 is mounted on the outer end of the latch pin 14 to enable the latch pin to be withdrawn manually from engagement with the recess in the horn guard when the guard is to be removed from the horn.

The tension mechanism of the machine illustrated in the drawing is mounted in the base of the horn and has the same construction, arrangement and mode of operation of parts as the corresponding mechanism illustrated and described in applicant's pending application, Serial No. 80,911, filed February 28, 1916. The tension mechanism comprises a tension wheel 18 about which the thread passes on its way from the supply to the whirl or looping device in the tip of the horn. The tension wheel is mounted upon a shaft 20 engaging in bearings in the wall of the horn and extending through the wall of the horn to the exterior thereof. Upon one end of the shaft

20 is mounted a brake wheel 22 and a pair of pivotally connected brake shoes 24 and 26 are supported on the periphery of the brake wheel and are held from rotation therewith by means of a screw 28. The brake shoes 24 and 26 are acted upon by a coiled spring 30 which normally holds the brake shoes in yielding engagement with the brake wheel to retard the rotation of the shaft 20 and the tension wheel.

To enable the thread to be relieved of tension so that it may be drawn freely about the tension wheel, a lever 32 is pivoted on one end of the shaft 20 and a second lever 34 is pivoted at 36 on the lever 32. The lower end of the lever 32 is arranged to engage an extension on the brake shoe 24, and the shorter arm of the lever 34 is arranged to engage a lateral projection on the brake shoe 26. The longer arm of the lever 34 is formed with a thumb plate 38 by means of which the operator may depress this arm of the lever. The thread indicated at 7 in the drawing passes upwardly through the base of a horn about the tension wheel 18 under a thread truck 41 mounted in the horn, and thence upwardly through the horn. By pushing the forwardly extending arm of the lever 34 downwardly, the levers 34 and 32 are relatively actuated to separate the lower ends of the brake shoes and thus relieve the pressure of the brake shoes on the brake wheel.

In order to protect the uppers of the shoes 35 from oil, wax or dirt which might be deposited thereon by the contact of the uppers with the parts of the tension mechanism, the tension mechanism is enclosed by a casing mounted on the base of the horn. This casing 40 comprises two hollow sections 40 and 42 arranged to surround the base of the horn and to enclose the parts of the tension mechanism, as shown in Fig. 1. Each of the sections of the casing is movably mounted on the horn so that the casing may be opened to expose the parts of the machine 45 enclosed by the same. The section 40 of the casing which encloses the tension wheel brake mechanism is pivoted on a stud 44 carried by a bracket 46 secured to a flange 48 on the base of the horn. The section 42 which encloses the left hand end of the tension wheel shaft and other parts on the left side of the horn, Fig. 2, is pivoted on a stud 50 carried by the bracket 46. This manner of mounting the two sections of the casing enables each of these sections to be swung in a horizontal plane toward and from the base of the horn. Figs. 1 and 3 55 illustrate the sections of the casing in closed positions, while Fig. 2 shows the same in open positions. The two sections of the casing when closed surround the base of the horn, the section 40 being cut away at 52 and the section 42 being cut away at 54 to

receive the horn. In order to hold the sections of the casing in closed positions, a latch 56 is secured at 58 to the section 42 and is provided at its free end with a projection arranged to engage a projection 60 on the section 40. The body of the latch 56 consists of spring metal and is bent so that the free end of the latch tends to spring inwardly toward the section 40, and the latch is provided with an inclined face 62 for engagement with the projection 60 to throw the free end of the latch outwardly when the sections of the casing are being closed.

To enable the lever 38 to be actuated to relieve the tension on the thread without opening the casing, the section 40 of the casing is provided with an opening 64 through which the longer arm of the lever projects to the exterior of the casing.

When the casing is open, as shown in Fig. 2, the parts of the tension mechanism are accessible for oiling or adjustment and the horn guard 12 may be readily removed to enable the machine to be threaded.

Having explained the nature and object of the invention, and having specifically described a machine embodying the invention in its preferred form, what is claimed is:

1. A shoe sewing machine having, in combination, stitch forming devices including a straight hook needle, a rotatable work supporting horn, a tension device mounted at the base of the horn, a casing enclosing the tension device having an opening therein, and a tension release lever mounted within the casing and extending through the opening in the casing to the exterior thereof.

2. A shoe sewing machine having, in combination, stitch forming devices including a straight hook needle, a rotatable work supporting horn, a tension device mounted at the base of the horn, a casing for enclosing the tension device comprising two sections pivoted to swing in opposite directions in a horizontal plane from closed to open positions, and a latch for holding said sections normally in closed position.

3. A shoe sewing machine having, in combination, stitch forming devices including a straight hook needle, a rotatable work supporting horn, a tension device mounted at the base of the horn comprising a tension wheel mounted within the horn, a tension wheel shaft engaging in bearings in the wall of the horn and extending through said wall to the exterior thereof, a brake wheel mounted on one end of said shaft, a brake shoe engaging the brake wheel, means for engaging the brake shoe with the brake wheel, devices for relieving the pressure of the brake shoe on the brake wheel, a casing for enclosing the tension device comprising a section enclosing the brake mechanism pivoted to swing in a horizontal plane, a second section for enclosing the other end of the tension wheel

shaft also pivoted to swing in a horizontal plane, and a latch for holding said sections in closed position.

4. A shoe sewing machine having, in combination, stitch forming devices including a straight hook needle, a rotatable work supporting horn, a tension device mounted at the base of the horn, and a casing for en-

closing the tension device comprising two sections pivotally mounted on the base of 10 the horn to swing in opposite directions in a horizontal plane from closed to opened positions, said sections being cut away to receive the horn and when in closed position surrounding the base of the horn.

WILLIAM C. MEYER.
